UNITED STATES PATENT OFFICE.

GEORGE RAMSEY, OF BROOKLYN, NEW YORK, ASSIGNOR TO ANCHOR CAP & CLOSURE CORPORATION, OF BROOKLYN, NEW YORK, A CORPORATION OF NEW YORK.

PAPER CLOSURE.

Application filed April 11, 1918, Serial No. 227,874. Renewed September 3, 1921. Serial No. 498,573.

To all whom it may concern:

Be it known that I, GEORGE RAMSEY, a citizen of the United States, and a resident of the city of Brooklyn, in the county of 5 Kings, State of New York, have invented certain new and useful Improvements in Paper Closures, of which the following is a specification.

This invention relates primarily to closures and more particularly to a closure made 10 principally from paper-stock.

The principal object of this invention is the provision of a cheap closure that can be tightly secured on container mouths of 15 variable dimensions.

A further object of this invention is to provide a closure that may be tightly sealed against a substantially straight walled container mouth and wherein the major portion 20 of the closure is formed of paper stock and the minimum portion of metal.

A still further object of the present invention is the provision of a closure of the side seal type wherein the closure proper is 25 formed from paper stock and the sealing bead is reinforced by a metallic ring that is adapted to enclose a bead that is formed in the side wall of the paper stock cap.

Another object of the present invention is 30 the provision of a closure of the character specified and wherein the bead retaining ring is formed of sheet metal and positioned upon the cap at the time the bead is formed in the cap.

Other and further objects of the present 35 invention will in part be obvious and will in part be pointed out hereinafter in the specification by reference to the accompanying drawings and wherein like parts are represented by like characters throughout the several figures thereof.

Figure 1 is a sectional view illustrating the 40 cap in position on a container neck ready to be sealed.

Figure 2 illustrates the relation of parts 45 after the seal has been completed by use of one type of sealing die.

Figure 3 is a sectional view of a different 50 type of seal.

Figure 4 is a section taken through the 55 middle of the sheet metal reinforcing ring with the paper stock cap removed.

Figure 5 is a perspective view of a completed ring with the paper stock removed.

Figure 6 diagrammatically illustrates a 55 mechanism for spinning or rolling the sheet metal ring in position on the cap.

Figure 7 is a view taken on section A—A in Figure 6.

Heretofore in the art of closures it has 60 been common practice to gather a sheet of paper over the mouth of a container and tie such sheet of paper in position with a string. It has also been common practice to provide a paper cap that is tied in position 65 on a bottle neck, for example a milk bottle, by means of a contracting metal ring. The first method is usually carried out by hand and in substantially all cases makes an insecure closure that requires considerable 70 time to be properly positioned and secured in place. The second type of closure more nearly approaches the present invention but in this type of closure the forces acting to contract the metal tie are restricted to a 75 single zone and must be so regulated as not to crush the container during the sealing operation, and therefore are liable not to make a fluid tight or hermetic seal. Furthermore, in this type of closure more or less 80 complicated mechanism is necessary for sealing and such seals are not adapted for use against straight walled containers.

The present invention provides a side seal 85 of great strength and security and of such formation and simplicity as to permit the sealing operation to be accomplished by sealing dies of very simple construction and in general use in sealing sheet metal closures. By treating the paper stock with suitable 90 water-proofing materials it is possible to use the present closure to obtain hermetic seals which may be largely used to replace sheet metal closures in many classes of packages.

Referring now more particularly to the 95 drawings the major portion of the cap 1 is formed from paper stock either by punching, or punching and drawing, from suitable sheets of paper, a plain straight walled cap. A groove or bead 2 is provided in the cylindrical side wall of the paper cap 1 and is preferably V-shaped in cross section. The exterior of this groove is reinforced by a sheet metal ring or band 4, the ends of which are overlapped, as at 5 in Figures 4 and 5. 100 This reinforced paper cap is adapted to be placed over the mouth of a container 6 of glass, earthenware, or other substantially 105

incompressible material. After the cap is placed in position the seal is effected by squeezing together or compressing the upper and lower walls 7 and 8, respectively, of the sheet metal band or ring 4, while constraining the ring and skirt against the peripheral wall of the vessel. This action may be accomplished by suitable sealing dies 9 and 10 that are relatively movable and provided with properly related sealing faces, as is common in the art. It will be noted that since the ring 4 cannot expand diametrically to the full width of the folded portions, the bringing together or closing of the upper and lower side walls causes the inner edges of the ring to move inwardly, thereby constituting a tension member compressing the paper stock tightly against the outside wall of the container 6, and effecting a very tight seal between the side wall and the paper cap. The seal formed in this manner is in reality a double seal, one complete peripheral sealing zone being formed between the upper wall 7 of the ring and the side of the container, and a separate complete peripheral sealing zone being formed between the lower wall 8 of the ring and the side of the container. Either of these seals will be effective in maintaining the container properly closed. Where the paper cap is paraffinized or otherwise treated, the water-proofing material will be, to a certain extent, forced from the pores of the cap at the sealing zone and will form a layer of such material between the cap and the container, thereby further facilitating the hermetic seal. It will be noted that the sealing zone is relatively wide in that it will include substantially the entire area beneath the compressed ring or band 4.

In Figure 3 is illustrated a seal formed by angularly disposed sealing dies. In this type of seal the upper edge or wall 7 of the ring 4 is bent upwardly thereby producing a more acute angle between the bead and the side wall of the cap, consequently increasing the radial pressure at this zone and thereby effecting a slightly wider sealing area than is obtained in the seal illustrated in Figure 2. In this construction the sealing faces on the sealing dies or chucks 11 and 12 are inclined and substantially parallel.

Figures 6 and 7 illustrate diagrammatically one form of mechanism for spinning the ring 4 in position upon the cap and this mechanism may comprise a supply of strip sheet tin 14 that is led over the guide roll 15 and through the feeding rolls 16 and 17, past the cutting blades 18 and 19 through the guide 20 to the grooved pressure rolls 21 and 22. These pressure rolls are mounted on a suitable spring-pressed saddle and may be lifted when desired by suitable mechanism (not shown). These rolls 21 and 22 bear

against the bead roll 24 that is mounted within a suitable guide 25. Assuming that the pressure rolls 21 and 22 have been lifted and that a paper cap 1 has been positioned on the bead roll 24: Now when the feeding rolls 16 and 17 advance the strip of tin from the supply 14 through the guide 20 to the pressure roll 21, this strip of tin will be caught between the pressure rolls and tightly compressed against the paper cap and continuing the rotation of the various rolls will feed the strip of tin around the paper cap and at the same time bead or groove both the tin and the side wall of the cap. When a suitable amount of tin has been fed forward to complete the ring the cutters 18 and 19 are very quickly operated to sever the supply and the complete cap is then ready to be removed from the device. The several operations take place automatically so that the caps are very quickly and economically formed. Under some certain conditions it is desirable to have intimate contact between the ring 4 and the cap 1 and where this is desirable an intermediate material, such as resin and talc or other suitable adhesive materials, may be utilized for coating the strip of tin on the side which contacts with the paper cap so that during the beading operations sufficient heat will be developed to cause the ring to stick to the side walls of the cap.

The present invention contemplates a cap the major portion of which may be formed of some inexpensive flexible material such as paper, the necessary rigidity for effecting a permanent seal being contributed by a reinforcing member of flexible material having a greater stability than the inexpensive material, so as to act, when applied to the container, as a tension member effective to retain the flexible material of the cap under compression against the container wall. This provides a cap both economical in manufacture and in application, and wherein no metal is in contact with the contents of the container, and also wherein an effective liquid and hermetic seal is established.

Having thus described my invention what I claim is:

1. A closure of the character specified comprising a cap of paper and the like having a top portion and a depending skirt, a bead in the said skirt with the concave portion of the bead on the interior of the skirt and the convex portion of the bead on the exterior of the skirt, and a reinforcing band covering said bead, said band being formed of material having greater stability than the material in the cap and adapted when compressed to cause said bead to be collapsed and to produce an inward radial movement of portions of the skirt whereby said cap may be sealed against a substantially

incompressible side wall of a suitable container.

2. A closure of the character specified comprising a cap of paper or the like and having a cover portion and a skirt depending from said cover portion, said cap being treated with water-proofing material to substantially fill the pores thereof, a bead in the skirt of said cap with the concave portion of said bead on the interior of said skirt and the convex portion of the bead on the exterior of said skirt, and a reinforcing band overlying said bead, said band being formed of material having greater stability than the cap material so as to maintain the latter in position and express water-proofing material from portions thereof.

3. In a closure of the character specified, a cap of paper and the like having a cover portion and a skirt depending from said cover portion, an annular bead in said skirt, a reinforcing metallic means on the exterior of said skirt and constructed to collapse the said bead when the side walls of said means are collapsed whereby said means is capable of retaining the said bead in conformity with the contour of the said means.

4. A container comprising a receptacle having substantially incompressible side walls adjacent the mouth thereof, a closure in the form of a cap of paper or the like and having a cover portion, and a skirt portion, a sealing bead in said skirt comprising a portion of said skirt folded upon itself, and retaining means for preventing the unfolding of the folded portion and to maintain the skirt adjacent the folded portion under radial pressure and in close contact with the side walls of the container adjacent the mouth thereof.

5. A package comprising a container, a paper cap having a cover portion and a skirt depending over the side walls of the said container, a bead in said skirt, and reinforcing means substantially U-shaped in cross-section and maintaining the skirt adjacent said bead in close engagement with the side walls of the container to form a hermetic seal between the side walls of the container and the said skirt.

6. A device of the character specified comprising a paper cap having a cover portion and a skirt depending from said cover portion, a bead formed in said skirt and an open band over said bead whereby said band may be deformed to deform said bead and thereby effect a seal between said skirt and the side walls of a suitable container.

7. A closure comprising a cap portion of flexible material shaped to provide a top and an annular skirt, and a tensioning member of flexible material having greater sta-

bility than the material of the cap encompassing the skirt portion; the tensioning member and skirt being formed with registering beads protruding convexly on their peripheries, for the purpose described.

8. A package comprising a container having a side wall, a cap of flexible material having a cover portion forming a closure for the container and an annular skirt encompassing the side wall, and a constricting member of ductile material having greater stability than the material of the skirt encompassing the skirt portion; said constricting member having parts deformed to maintain portions of the skirt compressed against the side wall in separate peripheral sealing zones.

9. A package comprising a container having a side wall, a cap having a cover closing the mouth of the container and a skirt portion encompassing a portion of the side wall; said skirt portion being deformed to provide a plurality of separate and independent hermetic seals between the skirt portion and the side wall of the container.

10. A closure for packing vessels comprising a cover for closing the mouth of the vessel, a ductile portion arranged to encircle the side wall of the vessel, and a flexible portion arranged to encircle the side wall of the vessel, the ductile portion being deformed upon the flexible portion to press parts thereof against the vessel wall to provide a plurality of separate peripheral hermetic seals thereon.

11. A closure cap having an integral paper cover portion and a depending skirt, a supporting member over the sealing portion of said skirt, said skirt having a groove adapted to be deformed to bring the side walls of the groove together and shorten the skirt whereby a portion of the skirt of the cap may be squeezed against the side of a suitable container and tightly supported thereon to form a side seal.

12. A closure cap having a paper cover portion and a skirt depending from the cover portion, said skirt being provided with a groove which is adapted to be deformed to decrease in diameter when vertically compressed and to form a friction side seal with the side wall of a suitable container, and means to hold said skirt in the deformed shape.

13. As an article of manufacture, a closure cap having a cover portion and a skirt portion of compressible paper stock or the like, and a constricting band encircling said skirt portion and being provided with an open groove adapted to be deformed to squeeze the skirt of the cap against the side wall of a suitable container and form a side seal.

GEORGE RAMSEY.
